DIALING ATTACHMENT FOR A WRITING
INSTRUMENT OR THE LIKE

Owen Morris, 69—76 113th Ave., Forest Hills, N.Y.

Filed Oct. 2, 1958, Ser. No. 52,852

Term of patent 14 years

(Cl. D74—1)

FIG. 1.

FIG. 2.

FIG. 3.

FIG. 4.

Fig. 1 is a side elevational view of a dialing attachment for a writing instrument or the like showing my new design;

Fig. 2 is a side elevational view thereof turned at an angle of 90°;

Fig. 3 is a top plan view; and

Fig. 4 is a cross-sectional view taken on the line 4—4 of Fig. 1.

The dominant features of the design reside in the hexagonal stem portion combined with the flat faces of the triangular shaped head being disposed in substantially the same plane as every other face of the stem, all as shown.

The writing instrument shown in broken lines in Figs. 1 and 2 is merely for illustrative purposes.

I claim:

The ornamental design for a dialing attachment for a writing instrument or the like, substantially as shown and described.
